MEANS FOR ASEPTIC TRANSFER OF
STERILE ARTICLES

Carl W. Walter, Newton, Mass.

Application February 12, 1941, Serial No. 378,607

12 Claims. (Cl. 21—90)

In hospital practice, especially in the surgical operative field, it is essential to grasp and transfer numerous different sterile articles such as instruments, sponges, supplies and the like. These vary widely in shape, weight and bulk as from a milliner's needle to a heavy retractor or a sizable package of drygoods. The sponge stick and the utility forceps commonly used for such transfer are recognized as potential sources of danger to the sterile condition of the articles and supplies transferred.

As a precaution the transferring implement usually is placed in a germicide during idle periods, but so far as I am aware no satisfactory technique has been developed to insure that its article-engaging parts retain their sterile state until wholly clear of the germicide container. Most hospitals continue the use of relatively awkward and make-shift devices for the purpose. Yet it has been demonstrated that exposed portions of the germicide containers, particularly the neck, mouth and lip of the vessel, carry various pathogenic microorganisms, whether the containers are in actual use in the operating room or merely exposed in the hospital wards. This is in part due to the fact that, excepting certain formaldehyde-alcohol solutions and a few of the borax-formalin type, many of the chemical solutions widely used in the supposed sterilization of such vessels, instruments and other surgical supplies, while reasonably effective in destroying vegetative forms of bacteria of the non-sporulating variety, are relatively ineffective against the extremely resistant bacterial spores.

My present invention is concerned with the article-transfer problem as above indicated. It has as an important object the safeguarding of the article-engaging portions of the particular transfer instrumentality not only during idle periods but also throughout the course of their complete withdrawal and clearance from the germicide container, without reducing the ease and rapidity of such action or of the subsequent return of the transfer device to the germicidal supply.

In the drawings, illustrating by way of example one embodiment of means in accordance with the invention:

Fig. 1 is a side elevation of a sterile forceps unit showing the instrument in protected waiting position, a lower portion of the germicide vessel being broken away;

Fig. 2 is a generally similar view as Fig. 1 but with the instrument elevated as during removal or replacement;

Fig. 3 is a vertical section of the cooperating

container and shield elements, on a larger scale, a portion of the instrument jaws being shown as during their final emergence or initial reentry;

Fig. 4 is a partial vertical section as on the line 4—4 of Fig. 1, on a similar scale as in Fig. 3;

Figs. 5 and 6 are respectively a side elevation and a bottom plan of a floating shield element of the invention, also on the larger scale;

Figs. 7 and 8 are a plan and a cross section on the line 8—8 of Fig. 7, showing one of the forceps jaws separately on an enlarged scale; and

Figs. 9, 10 and 11 are further detail views of the forceps jaws, being respectively a side elevation, a longitudinal section and front end view.

15 Referring now to the drawings in more detail, the instrument and container assembly comprises a vessel or jar 10, here of general cylindrical form, having a height to contain the desired lower portion of the instrument to be kept in 20 sterile condition. This container 10 may be molded or otherwise formed of a material adapted for use with germicidal chemical solutions, including various of the plastics and synthetic compounds, preferably of the transparent or semi-transparent 25 variety. A fairly heavy glass of the usual laboratory type is well suited to the purpose.

The jar 10 is formed with a base 11 ample for the purposes of stability and desirably of the saucer-like form substantially as shown, to 30 serve as a drip catcher and receiver for spilled germicide. Desirably the side wall of the jar is graduated to indicate the proper level for the germicidal liquid, as indicated for example at L, Figs. 1 to 3.

35 The jar proper 10 is open at the top, where it terminates in an outturned rim 12. The latter is enclosed in and provides a firm seat for a plate-like reducing ring 13 of rubber or other somewhat resilient and desirably solution-resistant material or composition. This ring element or annular rim-enclosure 13 has a central aperture 14 somewhat smaller in diameter than that of the jar proper, and in normal use is fixed 40 on the jar rim, the ring having for the purpose a downturned and reentrant skirt 15 engageable beneath the jar rim 12. When desired this ring or rim case 13 may readily be removed by springing 45 its skirt out from below the jar rim.

As best seen in Figs. 3 and 4 the underface of 50 the ring 13 has a formation as indicated at 16 conforming it to the mouth and rim of the jar and giving it a firm seat on the latter. The adjoining under-portion of said ring, about the periphery of its central opening 14 presents an annular shoulder 17 extending inwardly beyond

the inner surface of the jar wall and adapted to serve as a stop in a manner to be described. At its top face the ring 13 has an upright flange or lip 18 surrounding the aperture 14 in the ring and having a beveled or inclined outer lateral portion 19 on which the cover member 20, to be described, has a snug sealing fit.

The cover element 20 above mentioned is constituted as a combined closure for the jar 10 and a hand guard and barrier for the handle portion of the transfer instrument to which it is fixed. Such instrument is herein illustrated as a pick-up and general utility forceps, indicated as a whole by the numeral 30 and itself embodying novel structural features for this type of device, to be described.

Said combined cover and guard element 20 comprises a molded or other plate or disc of a material which may be similar to that of the jar ring 13, such as a rubber or like resilient composition. This disc member 20 is centrally apertured to receive the lock portion 31 of the forceps 30, with the forceps legs or shanks 32, 33 up to the lock protruding below it and the handle members 34, 35 extending above. At opposite sides of the central aperture of this cover-guard disc 20 are sockets 21, 22 adapted to snap firmly into position over opposed lateral extensions of the pivot element 36 of the forceps lock.

Thus the cover-guard element 20 normally is securely positioned on the forceps, with its aperture closed by the lock portion of the latter and by the resilient opening-defining wall means of said cover 20, affording in effect a variable aperture conforming to the inserted portion of the forceps and laterally yieldable further to open or to reclose the aperture snugly about the forceps. If desired, this peripherally flanged plate or disc-like cover-guard 20 may be removed for cleaning or replacement by distending it sufficiently to release the forceps pivot extensions from their receiving sockets 21, 22, permitting withdrawal of the forceps legs.

At its underface the guard-cover element 20 has a depending plug portion 23 preferably with a downwardly tapered peripheral wall, for easy positioning of this plug portion within the receiving aperture 14 of the jar ring 13. A downwardly projecting peripheral flange 24 surrounds said plug portion, and is spaced from the latter to provide an annular channel 25 for snug sealing reception of the previously mentioned upright flange 18 on the jar ring 13. As seen in Figs. 2 and 4, the inner wall 26 of said cover flange 24 is beveled or outwardly inclined to conform to the bevel 19 of the ring flange 18. Accordingly, the cover element has an easy and assured firm seating action on the ring, requiring no special attention in placing it in jar-closing position, in which it effectively prevents the evaporation of the germicidal content.

The grasping and transfer instrumentality proper, as above noted, is of the forceps type. But instead of the usual straight handle end with terminal finger rings, I have provided it with a pistol-grip handle element, comprising the previously mentioned handle members 34, 35. These are disposed at an angle of preferably at least 45° to the forceps legs 32, 33, so affording a stronger and more natural grip; see particularly Figs. 1 and 2. This angular relation of grip and legs has the further advantage of naturally projecting the forceps jaws in the axis of the user's forearm, in which position the load is easily han-

dled, with minimum chance of contaminating contact by misdirection of the forceps.

Desirably lateral projections 34a, 35a are formed near the angle of each handle member. These give additional purchase for the thumb and forefinger respectively, to overcome any tendency of the loaded instrument to twist in the hand and also make it substantially impossible for the handle to slip back into the palm of a large hand.

5 The handle members 34, 35 and hence also the shanks or legs 32, 33 normally stand somewhat open, as represented for example in Fig. 1, being yieldably urged toward such position by spring means. Such means is here illustrated as a unitary leaf spring 37 anchored at one end near the angle of one handle member, herein handle 35, and having a rounded portion 37a at its other end adapted to abut and have easy sliding contact on the inner face of the opposite handle member 34.

10 The attached end of the spring may seat in a guide formation or recess at the inner face of the handle 35, holding it against turning relative to the latter. It is demountably or otherwise held in place, as by a screw. The spring desirably is

15 constructed and proportioned to present the handle members substantially in the Fig. 1 position, when free of a user's hand, in which position the two handle members readily conform themselves to and are encloseable by the palm and fingers of the hand, similarly as in engaging the grip of a pistol, the thumb and forefinger coming naturally against the prominences 34a and 35a respectively. The forceps 30 in the entirety, including said spring 37, preferably is formed of a

20 chemical- and rust-resistant material such as one of the stainless steels.

The outer terminal portions or jaws 38, 39 of the forceps legs 32, 33 are specially constructed and arranged for maximum utility of the instrument, adapting it for picking up and grasping firmly any of the widely variant articles and materials as referred to in the introductory portion hereof.

Contributory to that end, the jaws are disposed at somewhat of an angle, inwardly toward each other, rather than as mere straight extensions in the longitudinal axis of their respective shank portions 32, 33. This allows the jaws to lie substantially parallel to each other in a slightly open position, say approximately one-half inch apart, and also enables them to remain more nearly in mutual parallelism throughout their opening and closing movements.

The jaws, each of which may be similar but oppositely disposed, are relatively narrow and have somewhat of a longitudinal taper, ending in a rather small externally rounded tip with a fairly sharp and almost blade-like inner edge, easily thrust beneath flat articles. In Figs. 7 and 8 one of the jaws is shown separately, in this case the jaw 38, at the end of the leg 32 integral with the handle member 34, this being the under jaw when the forceps is held with the user's thumb on top, on said handle 34, and the forceps legs extended horizontally. It will be understood however that the jaw portions proper may be substantially similar, although inverted relative to each other in the assembled instrument, so that what is said as to the jaw 38 of Figs. 7 and 8 is for the most part also pertinent to jaw 39, corresponding parts being indicated by similar reference characters; in this connection see also Figs. 9, 10 and 11. For purposes of description the portion of the forceps which is important to keep 70 sterile, below the pivot or lock location, including

at least the lower parts of the shanks or legs 32, 33 and their jaws, may be termed the infra-lock portion.

Referring now particularly to said Figs. 7 to 11, the jaws 38, 39 are concave at their inner faces, giving them an arcuate or crescentic form in cross section; Figs. 8 and 11. Their side edges taper toward the opposite jaw to relatively thin, sharp longitudinal crests. The two side-edge crests of each jaw are irregularly serrated, as at 38a, 38b, and are differently and non-oppositely recessed, upon arcs of different curvatures, as represented at 38c, 38d and 38e. In this instance one of the jaw side edges has two such recesses, 38c and 38d, the inner one 38d standing laterally opposite non-recessed serrated edge portions 38a, both of the same jaw and of the other jaw. The outer recess 38c is adjacent but spaced sufficiently from the tip of the jaw to provide for one or more serrations 38b between it and the terminal extremity of the jaw. Opposite this outer recess 38c of the plurality recessed jaw edge the other edge has the somewhat longer recess 38e extending substantially fully to the very terminal tip of the jaw, there forming a sharp terminal corner or single tooth 38f. The latter, in cooperation with the plural-toothed terminus of the oppositely arranged jaw, see Figs. 9 to 11, is adapted to pick up and hold firmly relatively minute articles and objects such as the smaller surgical needles, sutures, etc. In picking up such small articles the non-opposite single points or teeth 38f of the respective jaws serve in effect to lift and feed them into a position where they are grasped or clamped by the other teeth 38b; in this connection see particularly Figs. 9 to 11. The irregular and non-matching structure for the opposed jaws such as here illustrated and described by way of example, together with their length, special tip formation, and ability to open from a tip-contacting position at an inclination toward each other, through a position of parallelism, to open positions up to angles of 90° and more (the spring 37 being able to move away from handle 34 in the wider open conditions) affords for the forceps an extremely wide range of usefulness, importantly extending its capacity for general utility pick-up and transfer purposes.

As seen in Figs. 7, 8 and 11, the jaw 38, the one in the lower position when the forceps is held extended, may be formed with a drainage aperture 38g, through which the germicide which might otherwise be held in the concavity of the jaws may readily escape.

Claims directed to the forceps, whether with or without the lock-associated guard or supporting element, and apart from other features of the assembly unit, are contained in my copending divisional application Serial No. 475,135, filed February 8, 1943.

Returning now to the further consideration of the sterile conditioning assembly as a whole, there is further provided in cooperative relation both to the forceps and to the germicide jar 10 and its ring 13 a vertically movable or floating forceps escort element 40, seen in elevation in Figs. 1 and 2, in vertical section in Fig. 3, and separately in Figs. 5 and 6.

This floating escort or shield element 40 as illustrated is a tubular, and herein substantially cylindrical, cup or bucket, open at the top, and of a diameter sufficiently less than that of the jar to allow it to move freely up and down in the latter. It may be variously constructed, either of metallic or non-metallic material, de-

sirably rather light in weight and non-corrosive or resistant to germicidal and other liquids and able to stand steam or other heat sterilization. In the example of the drawings it is molded or otherwise formed of a chemical-resistant material such as "Bakelite" or others of the plastics, transparent or otherwise. In another form which in some respects I have found preferable this floating guard 40 is integrally or otherwise fashioned of a resistant metal such as stainless steel.

To allow for rapid inflow and discharge of the germicidal solution from the floating shield as it rises and falls, openings are provided in its walls, having a relatively large total area. As here shown by way of example and noting particularly Figs. 3, 5 and 6, the bottom of said bucket or cup 40 is perforated by a multiplicity of apertures 41. In addition its side walls are fenestrated, herein to different vertical extents, as by the alternating short and long slots or windows 42, 43, providing a large open area while maintaining adequate wall strength. The lower ends of these fenestrations extend into the bottom wall as evident in Fig. 5 and particularly in the bottom plan view, Fig. 6, thus increasing the apertured bottom area.

At its upper portion this floating bucket or cup-like shield 40 is formed externally with a lateral projection, interrupted or otherwise, such as the annular flange 44, the under wall of which provides a shoulder or abutment for receiving and seating upon the upper end of an upright spiral spring 45 formed preferably of stainless steel. The top wall of said flange 44 is adapted to engage the shoulder 17 of the jar ring 13 as a limiting stop for the upward movement of the bucket 40, as in the position shown in Fig. 3.

The lower end of the spring 45 seats with a natural centering action on the bottom wall of the jar 10, which wall may be slightly convex or otherwise formed to aid in positioning the lower end of the spring. Said spring has an overall length, weight, size and tensile strength readily to lift and yieldably support the bucket in its uppermost position, near or above the "full" liquid level, indicated by the graduation L, the bucket accordingly being then emptied or mainly so. The weight of the bucket 40 and the strength of the spring also are so calculated with respect to the weight of the forceps that the latter when inserted and dropped into the jar easily compresses the spring, the forceps jaws necessarily entering the bucket, and the bucket and the received infra-lock portion of the forceps distal to the handle being quickly submerged in the germicide. The quantity of germicidal solution displaced by the bucket as it sinks flows into the latter through the apertures or fenestrations 41, 42, 43, raising the fluid level in the jar, to somewhat above the "full" level L, assuming that the fluid content initially is sufficient to stand at said level L in the raised position of the bucket as in Figs. 2 and 3.

Referring now particularly to Fig. 3, also Figs. 2 and 5, it is especially to be observed that the cylindrical or other side wall of the bucket is extended upwardly well beyond its stop member or external flange 44. In the elevated position of the bucket, Figs. 2 and 3, its upper side wall accordingly extends through the adjacent peripheral portion of the jar ring 13 and projects well above the top of the latter, desirably for at least $\frac{1}{4}$ to $\frac{3}{8}$ of an inch. The outer wall of this top edge portion or rim of the bucket is in-

wardly beveled substantially as indicated at 46, facilitating the upward movement of the bucket and guiding it upwardly through the jar ring 13, should it happen to be off center. The aperture 14 of said ring preferably is somewhat larger than the adjacent portion of the bucket, as a further aid to the unobstructed upward forceps-escorting movement of the latter.

From the foregoing it will be understood, particularly with reference to Fig. 3, that when the forceps, being in their rest position as in Fig. 1, are grasped and lifted for use, the sterile bucket 40 travels upwardly with the forceps and guards the jaws against contamination from contact with any non-sterile portion of the jar. Hence the sterile jaws are escorted to a level substantially above and beyond any exposed part of the jar, including the stationary rim cover or ring 13. Thus the greatest source of danger to the forceps, that of contact of its jaws with the jar rim during their withdrawal, is positively eliminated. It is made substantially impossible for the sterile jaws of the forceps to contact any exposed non-sterile portion of the jar unless by deliberate effort. Accordingly the sterile assembly unit as herein illustrated and described by way of example affords a safe and efficient means for the ready conditioning of the transfer instrumentality and for the aseptic transportation of sterile articles to the operative field.

By the invention the instrument to be kept sterile is presented for use in upright position, with its importantly sterile portion immersed in germicide, the vessel being automatically covered in so positioning the instrument, and uncovered again automatically by its withdrawal. Further, the extremity of the instrument, where sterility is especially important, is safely escorted fully to and substantially beyond all exposed and likely septic upper wall, mouth and rim portions of the germicide vessel. And in returning the instrument after use the escorting means is itself automatically sterilized by subjection to the germicide.

It will be understood that my invention is not limited to the exemplary embodiment herein illustrated or described, and I set forth its scope in my following claims.

I claim:

1. A combined sterile transfer forceps and holder therefor comprising a germicide container having an open top, a forceps having jaw and handle portions, a removable cover for the container, means to suspend the forceps on the cover with its jaw portion at the inner side and at least its outer handle portion at the outer side, and a cup-like apertured shielding member in the container adapted to receive the lower jaw portion of the forceps, said members yieldably supported for vertical movement with the forceps on insertion and removal of the latter.

2. A combined sterile transfer forceps and holder therefor comprising a germicide container having an open top, a forceps having jaw and handle portions, a removable cap-like cover for the container, a variable aperture in said cover for the downward projection of at least the forceps jaw portion through it, movable wall means associated with said aperture to vary the opening thereof while permitting operative movement of the forceps jaw and handle portions, and attaching connections for the forceps and cover.

3. In a sterile transfer instrument and container unit, in combination, a tubular open-top

5 container for germicide, a forceps comprising handle and lock portions with associated shanks and jaws, the container adapted for reception of at least the major infra-lock portion of the forceps, and a laterally projecting cover plate element mounted on the forceps not lower than its lock, and seating means for said element at the top of the container and cooperable with said element to seat it on and to cover the open top 10 of the container and to suspend the forceps with said infra-lock portion in the container and its handle portion projecting above the latter conveniently to a user's hand.

4. A sterile transfer instrument and container 15 assembly comprising, in combination, an upright container having an open mouth at its top, a transfer instrument of the forceps type including jaw and handle portions and a pivotal lock, said container and instrument being mutually 20 adapted for reception at least of the instrument jaw portion within the container, and a fenestrated bucket in the container and adapted to receive the instrument jaw portion, said bucket being vertically movable between an upper position 25 wherein its rim projects above the container mouth and a downward position of submergence in the fluid content of the container, stop means limiting said upward movement, and resilient means urging the bucket upwardly.

5. A sterile transfer instrument and container assembly comprising, in combination, an upright container having a projecting base and an open top, a transfer instrument comprising pivoted main elements each having a handle portion at 30 one end and a jaw at the other, said container and instrument being mutually adapted for the insertion at least of the instrument jaws well down into the interior of the container, a removable cover for the top of the container, said cover being apertured for laterally extensive positioning on and attachment to an intermediate portion of the instrument, and said handle portions of the instrument being disposed at an angle to their corresponding jaws so as together 35 to provide a pistol grip, said grip, in the seated position of said cover, being angularly extended above the container with its axis substantially paralleling the transverse axis of a naturally approaching palm of a user's hand.

6. A sterile transfer instrument and container assembly comprising, in combination, an upright container having a projecting supporting base and an open mouth at its top, a transfer instrument comprising pivotally associated elongated main elements each having a handle portion at one end and a jaw at the other, said container and instrument being mutually adapted for the insertion at least of the instrument jaws through the mouth of and well down into 55 the interior of the container, a bodily displaceable cover adapted to seat on and in closing relation to the mouth of the container, said cover being apertured to receive and support the instrument at a longitudinally intermediate portion thereof, interconnections for the instrument and cover adjacent said aperture, the cover including means at said aperture movable in the plane thereof to accommodate relative pivotal manipulation of said main elements of the transfer instrument.

7. A sterile instrument and container assembly comprising, in combination, a liquid container adapted to stand erect and having a top opening, an instrument having at one end pivotally related jaws receivable in the container and

having a hand grip at its other end, a closure for the container top opening, said closure constructed to support the instrument on the container in freely available upright position with the hand grip projecting from and wholly outside the container in constant readiness for instant removal and operative manipulation of the instrument thereby, interconnecting formations between the closure and the instrument adjacent its jaw pivot, and yieldably supported jaw-guarding means vertically movable between projecting and housed positions in and relative to the container attendant on insertion and withdrawal of the instrument and whereby the instrument jaws can engage only said jaw-guarding means during such withdrawal.

8. A sterile instrument and container assembly comprising, in combination, a liquid container having a top opening, an instrument having at one end pivoted jaws receivable in the container and having a hand grip at its other end, means for supporting the instrument with its jaws depending inside and its hand grip projecting outside the container, an open-top bucket having bottom and side walls including a top rim, the bucket adapted to receive the instrument jaws and being disposed for vertical movement in the container between an upper position in which the bucket top rim is projected up through and beyond the top opening of the container and a lower position in which the bucket is immersed in the liquid of the container, spring means for lifting the bucket to and holding it in its upper position, coactive positioning means on the container and bucket to determine said upper position of the bucket, and liquid inlet and outlet means on the bucket below its rim, the bucket and its spring means being constructed and arranged for depression of the bucket to immersed position automatically by the weight of the inserted instrument and for upward escorting movement of the bucket with the instrument during its withdrawal.

9. A combined transfer instrument and sterilizing receiver, comprising, in combination, an open-top jar adapted to receive liquid and the lower part of an instrument to be sterily conditioned, an instrument of the pivoted jaw type, a removable plate having a peripheral flange for positioning it on and in top-closing relation to the jar, said plate having at a central portion an aperture for insertion of the instrument and installation of the plate thereon intermediate its ends, means for securing the plate and instrument to each other in said installed position, and movable means at the aperture of the

plate for varying the opening thereof attendant on relative movement of the instrument jaws.

10. A sterile transfer forceps and container assembly comprising, in combination, a tubular container having a supporting base and an open top including a circumferential rim, a cover-seating annulus fitted on the rim and having a large central opening, a forceps having at least its jaw lower shank portion insertable through said opening, a cover plate adapted to seat freely on said annulus to close its opening, an aperture in the cover plate for installing it on the forceps between the extremities of the latter, and means securing the forceps and cover plate together in said installed position, the cover plate having movable means at its aperture closing it against the adjacent portion of the forceps and movable to accommodate closing and opening motion of the forceps.

20 11. A sterile transfer forceps and container assembly comprising, in combination, a tubular container having a supporting base and an open top, a forceps having jaw and shank portions receivable in the container, a plate element mounted in transversely projecting position on an intermediate portion of the forceps and adapted to cover the container top and to suspend the forceps with its portion below said element received in the container, a tubular guard vertically movable in the container, said guard having an open upper end adapted to be projected through the open top of the container and being otherwise openly formed for free vertical movement in and relative to a liquid in the container, 30 said guard adapted to receive the jaw portion of the forceps and automatically to be depressed by the weight of the forceps on insertion of the latter into the container, and means urging the guard upwardly so as to escort the forceps jaw portion to and beyond the top of the container on withdrawal of the forceps.

12. A sterile instrument and container assembly comprising, in combination, a liquid container having a top opening, an instrument having at one end pivoted jaws receivable in the container and having a hand grip at its other end, a closure for the top opening of the container, said closure having an aperture for mounting it on the instrument so as to support the latter upon the container with its hand grip external thereof, attaching formations intermediate the closure and the instrument adjacent its jaw pivot, and movable means at the closure aperture for varying the latter with the relative movement of the instrument jaws.

CARL W. WALTER.
